(57) **CLAIM**

The ornamental design for a film can clock, as shown and described.

DESCRIPTION

FIG. 1 is a perspective view of the film can clock;

FIG. 2 is a front view of the film can clock;

FIG. 3 is a back view of the film can clock;

FIG. 4 is a right side view of the film can clock; and,

FIG. 5 is a left side view of the film can clock.

The broken lines shown in FIG. 3 are for illustrative purposes only and form no part of the claimed design.
